HYDROMETER BARREL PLUG

John Z. Hoyer, Conshohocken, Pa., assignor to
 Kimble Glass Company, Vineland, N. J., a
 corporation of Illinois

Application September 18, 1936, Serial No. 101,511

1 Claim. (Cl. 265—45)

This invention relates to hydrometers of the type in which the liquid to be tested is drawn into a transparent barrel and retained therein during the testing operation.

One of the primary objects of this invention is to provide a plug for one end of the barrel through which the liquid to be tested may be readily drawn into the barrel, the plug, however, being so constructed as to prevent the liquid from trickling out of the barrel during the testing operation.

A further object of the invention is to provide a plug of the above mentioned character which will be simple in construction and capable of economical production on a commercial scale.

Numerous other objects and advantages of this invention will become more apparent as the following description proceeds particularly when reference is had to the accompanying drawing wherein

Fig. 1 is an elevational view of a hydrometer showing a plug constructed in accordance with the teachings of this invention associated with the same;

Fig. 2 is a fragmentary sectional view of a portion of the structure shown in Fig. 1;

Fig. 3 is a transverse sectional view taken substantially on the line 3—3 of Fig. 2;

Fig. 4 is a transverse sectional view taken substantially on the line 4—4 of Fig. 2; and

Fig. 5 is a fragmentary longitudinal sectional view taken substantially on the line 5—5 of Fig. 2.

Referring to the drawing wherein like reference characters designate corresponding parts throughout all views, the numeral 10 designates a barrel which is preferably formed of glass or some other suitable transparent material and which is adapted to receive the liquid or solution to be tested. In accordance with the usual practice, the barrel is provided at its one end with a liquid suction and expelling bulb 12 and at its other end with an elongated suction tip 14 which is preferably flexible and which is provided with the passage 16 through which liquid may be drawn into the barrel. Disposed in the barrel is a hydrometer float 18 of any suitable construction.

The numeral 20 designates a plug by which the suction tip 14 is secured to and placed in communication with the interior of the barrel 10. This plug is formed of some compressible material such as rubber or the like whereby it may be snugly fitted in the open end of the barrel 10 and the plug is further provided with a laterally ex-

tending flange 22 which engages the adjacent free end of the barrel to form a liquid tight joint.

The body portion of the plug which fits snugly within the barrel 10 is provided in its outer periphery with an annular groove 24, this groove being preferably spaced from the outer end of the plug about three-quarters of the length of the plug. Communicating with the annular groove 24 is a passage 26 which extends inwardly toward the center of the plug and communicates at its inner end with a bore or passage 28 which opens through the outer end of the plug. At a point diametrically opposite the passage 26 the plug is provided with a second passage 30 which is relatively short and which communicates at its one end with the annular groove 24 and at its other end with a passage 32 which opens through the inner end of the plug and thus communicates with the interior of the barrel.

A nipple 34 formed of hard rubber or the like is preferably secured in the passage 28 and has its one end projecting beyond the outer end of the plug, the suction tip 14 being sleeved over and secured to the projecting end of this nipple as clearly illustrated in Fig. 5 of the drawing.

In using the device, the free end of the suction tip 14 may be inserted in the solution to be tested and the suction bulb manipulated to draw the solution upwardly into the barrel 10. It will be apparent that the solution will pass upwardly through passage 16 in the suction tip through bores 28 and 26 and into the annular passage formed between the inner wall of the barrel 10 and the plug by the annular groove 24. The liquid will flow around this groove and then be drawn into the barrel 10 by way of passages 30 and 32.

After the desired quantity of the solution has been drawn into the barrel 10, the suction tip may be removed from the solution to be tested and the reading taken on the hydrometer float. The passages in the plug 20 which place the suction tip in communication with the interior of the barrel are so arranged that the barrel does not communicate directly with the suction tip, with the result that liquid will not trickle from the interior of the barrel out through the suction tip during the testing operation. Additionally, it might be noted that the passages in the plug are so arranged as to form an air pocket within the plug which effectively seals the liquid in the hydrometer barrel making it necessary to compress the bulb 12 to expel the liquid from the barrel after the testing is completed.

While one embodiment of the invention has

been described with some detail, it is to be understood that the description is for the purposes of illustration only and is not definitive of the limits of the inventive idea. The right is reserved to 5 make such changes in the details of construction and arrangement of parts as will fall within the purview of the attached claim.

I claim:

10 In combination, a hydrometer barrel having an open end, a resilient plug inserted in the open end of said barrel, said plug having an axial passage extending from one end of said plug partly

through said plug, said plug also having a second passage extending from the other end of said plug partly through the plug and being out of alignment with the first-mentioned passage, said plug being further provided with a peripheral annular groove cooperating with the inner wall of the barrel to form an annular passage and having radial passages connecting said first and second mentioned passages with said annular groove, and an inlet nipple including a stem portion inserted 10 in said first-mentioned passage.

JOHN Z. HOYER.
